DESIGN FOR A DUSTPAN

William Jaffa, Minneapolis, Minn.

Application March 31, 1944, Serial No. 113,099

Term of patent 7 years

(Cl. D44—18)

To all whom it may concern:

Be it known that I, William Jaffa, a citizen of the United States and a resident of Minneapolis, in the county of Hennepin and State of Minnesota, have invented a new, original, and ornamental Design for Dustpans, of which the following is a specification, reference being had to the accompanying drawing, forming part thereof.

Fig. 1 is a top perspective view of a dustpan, showing my new design;

Fig. 2 is a side elevational view;

Fig. 3 is a front elevational view; and

Fig. 4 is a rear elevational view thereof.

I claim:

The ornamental design for a dustpan, as shown.

WILLIAM JAFFA.
